[57] CLAIM

The ornamental design for a charger, as shown and described.

DESCRIPTION

FIG. 1 is a front, top, and right side perspective view showing our new design for a charger with the cover closed and broken line matter being for illustrative purposes only and forming no part of the claimed design.

FIG. 2 is a left side elevational view of the design according to FIG. 1 with broken line matter being for illustrative purposes only and forming no part of the claimed design.

FIG. 4 is a bottom plan view of the design according to FIG. 1 with broken line matter being for illustrative purposes only and forming no part of the claimed design.

FIG. 5 is a front, top, and right side perspective view showing our new design for a charger according to FIGS. 1-4 with the cover open and broken line matter being for illustrative purposes only and forming no part of the claimed design.

FIG. 6 is a left side elevational view of the design according to FIG. 5 with broken line matter being for illustrative purposes only and forming no part of the claimed design.

FIG. 7 is a rear elevational view of the design according to FIG. 5 with broken line matter being for illustrative purposes only and forming no part of the claimed design; and,

FIG. 8 is a bottom plan view of the design according to FIG. 5 with broken line matter being for illustrative purposes only and forming no part of the claimed design.
